Primary Examiner — Kimberly Barnes(74) *Attorney, Agent, or Firm* — Warner Norcross + Judd LLP(57) **CLAIM**

The ornamental design for a vacuum cleaner, as shown and described.

DESCRIPTION

FIG. 1 is a front perspective view of a vacuum cleaner showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is an enlarged top view of the vacuum cleaner; and,

FIG. 8 is an enlarged bottom view of the vacuum cleaner. The broken lines in the drawings depict portions of the vacuum cleaner that form no part of the claimed design.
